EXERCISING DEVICE

Filed June 24, 1930

UNITED STATES PATENT OFFICE

FLORENCE L. GAILEY, OF LOS ANGELES, CALIFORNIA

EXERCISING DEVICE

Application filed June 24, 1930. Serial No. 463,455.

My invention relates to an exercising device and the principal objects of my invention are, to provide a relatively simple, practical and inexpensive device that may be conveniently used for simulating the movements of a person rowing a boat, thereby exercising practically all muscles in the arms, legs and torso.

A further object of my invention is, to provide an exercising device that is relatively simple in construction and which is not associated with any extraneous support or fastening means.

A further object of my invention is, to provide an exercising device that is capable of ready adjustment so as to be conveniently used by persons of different heights and different degrees of muscular development.

With the foregoing and other objects in view, my invention consists in certain novel features of construction and arrangement of parts that will hereinafter be more fully described and claimed and illustrated in the accompanying drawing, in which:

Fig. 1 is a top plan view of an exercising device constructed in accordance with my invention.

Fig. 2 is a side elevational view of the device.

Fig. 3 is a rear elevational view of the strap or band that is engaged by the head of the user.

Fig. 4 is a longitudinal section taken on the line 4—4 of Fig. 3.

Fig. 5 is a front elevational view of the foot engaging band.

Fig. 6 is an elevational view partly in section and showing a readily detachable link connection between one of the springs and the foot engaging band.

Fig. 7 is a sectional view showing a modified form of the foot engaging band.

Referring by numerals to the accompanying drawing which illustrates a practical embodiment of my invention, 10 designates a strap preferably formed of leather, which may be three or four inches in width and approximately eighteen or twenty inches in length and secured to the front face of this strap in any suitable manner, preferably by

rows of stitching 11, is a pad 12 of felt or other relatively soft flexible material. The central portion of the pad 12 is extended outwardly away from the strap 10, in order to form a rib 13 that acts as a dividing wall 55 or partition between the feet of the user when placed against the outer face of the pad. In some instances the pad of felt or the like may be secured to the leather strap by a suitable adhesive thus doing away with the necessity for stitching the pad to the strap.

Arranged on the face of strap 10, on the opposite side from the pad 12 are one or more longitudinally disposed straps or bands 14, of thin resilient metal, preferably steel, 65 and which function as a resilient reenforcement for the foot engaging member of the exercising device. These bands may be secured to the strap 10 in any suitable manner, preferably by means of rivets 15 and the ends 70 of the bands extend slightly beyond the ends of the strap 10 and such extending ends are formed into loops 16 that engage metal rings 17.

Detachably secured to the rings 17 are 75 links 18, each link being open on one side and the opening being normally closed by a sliding spring held tubular member 19 and engaging the opposite ends of these links 18 are the coiled end portions 20 of closely wound retractile springs 21. The opposite ends of these springs are provided with coil rings 22, to which are connected readily releasable links 23, that are identical in construction with the links 18 and said links 23 being also connected to the bail portions 24 of handles 25.

In the use of my improved exercising device, the user, lying on a bed, couch or on the floor, places the feet against the pad 12, adjacent to the rib 13 and with the hands grasping the handles 25, the feet and limbs are pushed forwardly and at the same time the user swings the body rearwardly and at the same time pulls the handles away from the foot engaging member and which action somewhat simulates the movements of a person rowing a boat.

The movements of the foot engaging member and the handles away from each other is yieldingly resisted by the springs 21 and as 100

the movements just described are repeated, practically all muscles in the arms, limbs and body of the user will be alternately stretched and contracted and thereby greatly benefited as a result of mild exercise.

5 The retractile springs forming a part of the device may vary in length and in tension so as to correspond to the varying height and strength of the different users and in 10 order to increase the adjustability of the device for the accommodation of persons of different heights, two or more of the readily detachably links may be used between the ends of the springs and the foot strap or 15 handles.

15 In order to provide a firm support for the seat while the device is in use, a relatively stiff member 26 of wood, metal or the like, is inserted between the central portion of 20 the pad 12 and the strap 10 and which member projects in both directions outwardly from the central rib 13. Thus a firm broad bearing for the feet is provided and the end portions of the pad will not exert inward 25 pressure against the sides of the feet while the same are positioned on that portion of the pad that is reenforced or backed by the relatively stiff member 26.

30 Where the foot supporting member is provided with the relatively stiff member, as illustrated in Fig. 7, it is possible to place the feet on the padded portion of the device in three or four different positions so that the 35 heels, arch or instep portions and the balls or toe portions of the feet may be effectively exercised.

35 In practice my improved device has been found very effective in the exercise and manipulation of the feet for the helpful treatment of fallen arches and other irregular 40 metatarsal conditions.

45 While I have shown the exercising device as being provided with two springs 21 on each side it will be understood that one or more springs may be utilized and in some instances it may be found desirable to use elastic bands instead of springs.

50 Thus it will be seen that I have provided an exercising device that is relatively simple in construction, inexpensive of manufacture and very effective in performing the functions for which it is intended.

55 The device is capable of ready adjustment to suit the height and strength of different users and the use of the device requires no supporting or anchoring means.

60 It will be understood that minor changes in the size, form and construction of the various parts of my improved exercising device may be made and substituted for those herein shown and described without departing from the spirit of my invention, the scope of which is set forth in the appended claims.

65 I claim as my invention:

1. An exercising device, comprising a flex-

ible foot engaging member, a strip of padding secured on one face of said foot engaging member and extending from one end thereof to the other, the central portion of said strip of padding being folded double and extended outwardly from the foot engaging member to provide a dividing wall, retractile springs connected to the ends of said foot engaging member and handles connected to said springs. 70 75

2. In an exercising device, a foot engaging member comprising a strap, a pad on one face of said strap, the central portion of said pad being folded double and projecting outwardly from the face of said strap to provide a dividing wall, a reenforcing member of resilient material secured to said strap on the opposite face from said pad, retractile springs detachably connected to the ends of said foot engaging member and handles detachably connected to said springs. 80 85

3. In an exercising device, a foot engaging member comprising a strap, a pad secured to one face of said strap, the central portion of which pad is folded double to provide an outwardly projecting transversely disposed rib, a reenforcing member of resilient material secured to the strap on the opposite face from said pad, retractile springs connected to the ends of said reenforcing member and handles connected to said springs. 90 95

4. In an exercising device, a foot engaging member comprising a strap, a pad secured to the front face of said strap, the central portion of which pad is folded double to form an outwardly projecting transverse rib and a reenforcing strip of resilient metal secured to the face of the strap opposite from said pad. 100

5. In an exercising device, a strip of resilient metal, retractile springs detachably connected to the ends of said strip, handles detachably connected to said springs, a pad secured to said strip of resilient material and the central portion of which pad is folded double to form an outwardly projecting transversely disposed rib. 105 110

6. In an exercising device, a strip of resilient metal, retractile springs detachably connected to the ends of said strip, handles detachably connected to said springs, a pad secured to said strip of resilient material and a transverse rib formed from the material composing said pad at the center thereof. 115

7. In an exercising device, a foot engaging member having a relatively stiff central portion and flexible end portions, a pad on the front face of said foot engaging member, the central portion of which pad is folded double to provide an outwardly projecting transversely disposed rib, retractile springs connected to the ends of said member and handles connected to said springs. 120 125

8. In an exercising device, a strap, a pad secured to one face of said strap, the central

portion of which pad is folded double to provide an outwardly projecting transversely disposed rib, a relatively stiff reenforcing member arranged between the central portions of said pad and strap, retractile springs connected to the ends of said strap and handles connected to said springs.

In testimony whereof I affix my signature.
FLORENCE L. GAILEY.
